Primary Examiner — Sandra L Morris(74) *Attorney, Agent, or Firm* — John S. Artz; Dickinson Wright PLLC(57) **CLAIM**

I claim the ornamental design for a plush bee, as shown and described.

DESCRIPTION

FIG. 1 is a front perspective view of a plush bee;
 FIG. 2 is a front view of the plush bee of FIG. 1;
 FIG. 3 is a rear view of the plush bee of FIG. 1;
 FIG. 4 is a right side view of the plush bee of FIG. 1;
 FIG. 5 is a left side view of the plush bee of FIG. 1;
 FIG. 6 is a top view of the plush bee of FIG. 1; and,
 FIG. 7 is a bottom view of the plush bee of FIG. 1.
 The broken lines in the drawings illustrate portions of the
 plush bee that form no part of the claimed design.
